REVERSE AIR FLOW CONVERTIBLE HOUSE-HOLD VACUUM CLEANER

Archie S. Browne, Detroit, Mich.

Application May 7, 1949, Serial No. 92,012

3 Claims. (Cl. 15—337)

1

The invention pertains to convertible vacuum cleaners and more particularly to small light weight vacuum cleaners for household use.

It is an object of my invention to provide a vacuum cleaner which is especially advantageous for use in residence houses and apartments because of its convenient light weight construction.

It is also an object of the invention to utilize in such a vacuum cleaner a reverse air flow principle for providing a very compact structure as well as providing a vacuum cleaner which is easily converted for use either as an upright or as a tank type vacuum cleaner.

It is a further object of my invention to provide such a useful light weight and compact vacuum cleaner in a structure which is simple and economical to manufacture and assemble.

Another object of my invention is to provide such a small compact light weight vacuum cleaner having the same high power air impeller means as utilized in my larger vacuum cleaner.

Further objects and advantages are within the scope of the invention, such as relate to the arrangement, operation and function of the related elements of the structure, to various details of construction and to combinations of parts, elements per se, and to numerous other features as will be apparent from a consideration of the specification in conjunction with the drawing disclosing specific embodiments of the invention, in which:

Fig. 1 is a side elevational view of the improved vacuum cleaner, with parts broken away and sectioned to show the end closure internal structure and parts also being shown by dotted lines;

Fig. 2 is a side elevational view of an alternative nozzle head embodying a rotary brush;

Fig. 3 is a front elevational view of the vacuum cleaner equipped with the head shown in Fig. 2;

Fig. 4 is an elevational view showing the air hose connector tube and a portion of the air hose; and

Fig. 5 is a fragmentary sectional view on line 5—5 in Fig. 1.

Referring more particularly to Fig. 1 of the drawing it will be seen that I have provided for this vacuum cleaner a rugged body consisting simply of a cylindrical member 11. This body is closed at the front end by means of a nozzle head 13, which is a disc-like plate adapted to fit upon the end of the body and having an internal flange 15 fitting therein, where it may be secured in any convenient manner, as by screws for example. A nozzle bracket 17 projects forwardly from the upper portion of this end 55 25 and then turns and enters the other end of

2

plate 13 and supports a nozzle 19 presenting a suction applying aperture 21, which is preferably elongated horizontally, for movement over surfaces or objects to be cleaned.

5 The nozzle 19 is provided with a conduit aperture 23 which is adapted, in any suitable manner as by a snug tapered fit, to receive the front end of a suction conduit 25 which passes back along the lower side of the cylindrical body toward the other end of the body, which is closed, and this end of the conduit is bent in for connection and securement into an orifice 27 in the sidewall of the body. Actually there are two such conduits 25 passing along under the body and spaced apart on opposite sides of the center or bottom line of the body where these conduits serve also as supports holding the body in a predetermined position when resting on the floor as may be seen in Fig. 3. The nozzle 19 of Fig. 1 is also elongated horizontally and is also provided with two conduit connection apertures on opposite ends or sides, as is the head shown in Fig. 3. Such air flow conduits 25 being of a suitable size for ample air flow capacity, and being attached at the ends to the vacuum cleaner, also serve very well as floor supports. And, if desired, additional spacers 28 and attachment means 30 may be provided to connect between these conduits and the body for greater strength and rigidity, as may be seen in Fig. 5.

As Fig. 1 shows, an electric motor 29 is mounted in the front end of the body 11 in axial alignment therein. The front end of the motor shaft 31 extends to the front end plate 13 and the other end of the motor shaft 31 extends back axially in the body through an open work spider 33 where it drives associated air impeller means 35 for drawing air along in the body toward the front end. The open work spider 33 has a collar 39 extending forwardly for securement by screws 41 to brackets 43 projecting into the body from the front end plate 13 in cooperating relation for mounting the electric motor. Bracket means 45 may be secured in the body for supporting the stators and cooperative parts of the air impeller, which may, if desired, be also secured directly upon the sidewalls of the outer body 11, as will be readily understood. As will be apparent, the particular motorized air impeller utilized is not critical or important and any suitable unit may be installed for this purpose.

The arrows represent the air flow in Fig. 1, from which it will be seen that after entering the nozzle slot 21 the air flows back in conduits 25 and then turns and enters the other end of

the body. From this point the air flow reverses and turns forwardly passing through the impeller 35, and then it is discharged laterally and downwardly from the body through a discharge port 47 provided in the sidewall of the body near the front end so that the air passes around the motor for cooling the motor and also it is discharged as remotely as possible from the person utilizing the vacuum cleaner.

To filter and clean the air any suitable filtering means 49 is mounted in the body 11 in the space through which the air must pass after it enters the body from the conduit 25 and moves toward the air impeller at the front end. Such a filter means 49 may consist of a bag of any suitable material having a rim 51 of yieldable material, such as rubber, around its open end where it is received on an inward flange 52 from a filter holding ring 53 secured on the sidewall of the body, and whereupon it is removably pressed by a filter holding member 55 having an external periphery 57 of circular shape and suitable size for clamping thereon. As shown, this filter holder 55 may be of a generally bowl shape with its rim 57 projecting laterally for this purpose. This bowl shaped filter holder member 55 has a central air passing orifice 56 and it is supported by brackets on fingers 58 in an end cap 59, also termed a handle cap, which fits upon the rear end of the body 11, so that installing the cap on the body also presses the rim 57 to hold and seal the rim of the filter bag upon the holding ring flange 52. The cap 59 is releasably secured on the rear end of the body in any suitable manner, as by releasable clips 61, which may be similar to such clips commonly provided on suitcases. Two or three such clips are ample to firmly secure the cap on the body, and the cap preferably has a flange 63 which fits into the end of the body for more secure fitting thereon.

The filter clamping hood or bowl 55 being clamped upon the filter, and the end of the body 11 being closed by the cap 59, the air flowing in from the conduits 25 passes through the orifice 56 and turns to move toward the front end of the body, in a reverse flow manner as represented by the arrows in Fig. 1.

The cap 59 is provided with a central aperture 60 opening axially therethrough into the body and this serves to receive and secure the stem 65 of any suitable handle 66. To convert the vacuum cleaner from an upright to a tank type vacuum cleaner, it is only necessary to pull out the handle and its stem 65 and insert therein an air hose connection tube 67, which is represented by dotted lines and partially broken away in Fig. 1. This tube 67, being longer than the handle stem, also extends in through the air passing orifice 56 in the filter holder 55. This plugs the air hose connector 67 in for connection through the filter to the air impeller and at the same time cuts off the air flow from the nozzle 19 through the conduits 25. The apertures 60 and 56 and the handle stem 65 and air hose connector tube 67 are, of course, made of suitable cooperative diameters for such interchangeable operation. And the hose connector tube 67 is of sufficient length to extend out through the end cap and have an air hose 68 thereon for utilizing various accessories in operation as a tank type vacuum cleaner.

The handle stem 65 and the hose tube 67 may be secured in the cap 59 by a suitable spring pressed retainer which may be quickly released

by pulling out on the nob 69 for quick change for operation either as an upright vacuum cleaner or as a tank type vacuum cleaner. The filter bag 49 is easily removed for cleaning or replacement by releasing clips 61 and removing the cap 59. Also a second or auxiliary filter 71 is then conveniently accessible to be removed, cleaned or replaced. This auxiliary filter 71 may consist, for example, of a textile fabric associated together with screen wire, for support in a circular form, engaging a perforated ring or disc 73 secured in the body 11, adjacent to but slightly spaced from the impeller.

It will be seen that I have provided a compact, convenient, light weight vacuum cleaner of a very simple construction, considering the wide adaptability thereof.

Figs. 2 and 3 show an alternate head 75 which may be installed upon this vacuum cleaner when it is desired to provide a vacuum cleaner having a rotary brush in cooperative relation with the cleaning nozzle. This head also has an end wall 77 which fits upon and closes the front end of the body 11 in air flow restricting relation except that a driving coupler 79 is rotatively disposed therein for operative connection from the extended front end of the motor shaft 31 to a small belt pulley 81 in the head. From this small pulley 81 a belt 83 drives a large pulley 85 having a joined small pulley 87 from which a belt 89 drives a pulley 91, which is on the shaft 93 of the rotary brush 95 suitably journaled in the head to be rotated in cooperative relation in the slot 97 in the nozzle 98 for agitating surfaces for the effective cleaning, in a well known manner. This head has the pair of conduit connecting apertures or sockets 23 spaced on both sides for connection with the front ends of the conduits 25 which extend back in under the body 11, in the manner previously described, except that these conduits are shorter and do not extend so far across the front end of the vacuum cleaner body. This head has wall enclosure means 99 enclosing the driving and speed changing means, and providing a boss 101 with a bearing for the front end of a shaft 103 the other end being journaled in the end wall 77. Shaft 103 rotatively supports the joined pulleys 85 and 87.

It is apparent that within the scope of my invention modifications and different arrangements may be made other than herein disclosed, and the present disclosure is illustrative merely, the invention comprehending variations thereof.

What is claimed as the invention is:

1. In a small light-weight convertible vacuum cleaner, the combination of, a filter enclosing body cylinder having a discharge port opening laterally through the sidewall thereof near the front end, air flow obstructing wall means on the front end of said body cylinder, a dirt collecting nozzle projecting frontwardly from said wall means, motorized air impeller means mounted in the front end of said body cylinder for drawing air along toward the front end in said body cylinder and discharging it laterally through said discharge port, conduit means connected to draw air from said nozzle, said conduit means extending along the side of said body cylinder and opening through the sidewall of the cylinder near the rear end thereof, closure means closing the rear end of the body cylinder so that air is caused to flow rearwardly in said conduit means and then into the body cylinder and frontwardly toward the air impeller means, said closure means also forming an air hose plug-in

socket for receiving an air hose connector there-in, and means in the rear end of said body cylinder for cooperating with such an air hose connector for intercepting the air flow circuit or path from said nozzle and conduit means and to establish the connection of said plugged-in air hose with the air impeller means for operation as a tank type vacuum cleaner, and further characterized by said conduit means comprising a pair of air flow conduits suitably spaced apart to also serve as a floor rest to support said body cylinder in a horizontally disposed position when operating as a tank type vacuum cleaner.

2. A convertible vacuum cleaner comprising, a filter enclosing body of an elongated tubular con-formation having a discharge port opening laterally through the sidewall near the front end thereof, air flow obstructing wall means on the front end of said body, a dirt collecting nozzle projecting frontwardly from said wall means, motorized air impeller means mounted in said body for drawing air along toward the front end in said body and discharging it laterally through said discharge port, air conduit means connected to draw air from said nozzle, said conduit means extending along the side of said body from the front end toward the rear end and opening through the sidewall of the body near the rear end thereof, closure means closing the rear end of the body so that air is caused to flow rearwardly in said conduit means and then into the body and frontwardly toward the air impeller means, said closure means also being conformed for receiving an air hose connector for operation as a tank type vacuum cleaner, means for intercepting the air flow circuit or path from said nozzle and conduit means and establishing the connection of said air hose connector with the air impeller means for operation as a tank type vacuum cleaner, said air conduit means extend- 40 ing along the side of said body being wide enough to engage the floor and to serve as a floor rest when the vacuum cleaner is resting in a horizontal position for operation as a tank type vacuum cleaner, and further characterized by said con- 45 duct means consisting of a pair of air flow conduits suitably spaced apart to engage the floor and serve as a floor rest when the vacuum cleaner is disposed in a horizontal position for opera-tion as a tank type vacuum cleaner.

3. In a convertible vacuum cleaner, the com-bination of, a filter enclosing body cylinder hav-ing a discharge port opening laterally through

the sidewall thereof near the front end, air flow obstructing wall means on the front end of said body cylinder, a dirt collecting nozzle projecting frontwardly from said wall means, motorized air impeller means mounted in the front end of said body cylinder for drawing air along toward the front end in said body cylinder and discharging it laterally through said discharge port, conduit means connected to draw air from said nozzle, 10 said conduit means extending along the side of said body cylinder and opening through the side-wall of the cylinder near the rear end thereof, a closure cap closing the rear end of the body cylinder so that air is caused to flow rearwardly in said conduit means and then into the body cylinder and frontwardly toward the air impeller means, said closure cap being conformed to also provide a central aperture suitable to serve as an air hose plug-in socket for receiving an air hose connector tube therein, a filter holding bowl shaped member disposed in the rear part of said body cylinder and being centrally apertured for receiving the inner end of an inserted air hose connector tube intercepting the air flow circuit or path from said nozzle and conduit means and establishing the connection of such a plugged-in air hose to the air impeller means through said filter holding member for operation as a tank type vacuum cleaner, said conduit means being wide enough to engage the floor and serve as a floor rest for the vacuum cleaner resting in a horizontal position, and further characterized by said conduit means consisting of a pair of air flow conduits suitably spaced apart to serve also as a floor rest when the vacuum cleaner is dis- 20 posed in a horizontal position for operating as a tank type vacuum cleaner.

ARCHIE S. BROWNE.
